LOAD INTERRUPTER HOUSED FUSE CUTOUTS

George R. McCloud, South Milwaukee, Wis., assignor to McGraw-Edison Company, Milwaukee, Wis., a corporation of Delaware

Filed Feb. 3, 1959, Ser. No. 790,853

3 Claims. (Cl. 200—114)

This invention relates to new and useful improvements in load interrupter fuse cutouts and more particularly fuse cutouts of the housed type wherein provision is made for mechanically breaking the fusible elements subject to load current in an electric circuit.

More particularly, the instant application relates to an improvement to the housed fuse cutout and mechanical link break mechanism associated therewith as set forth in my Patent No. 2,820,868 which issued on January 21, 1958.

The principal object of this invention is to provide a fuse cutout having a fuse link which will interrupt the circuit under overload conditions and including manually operable means for breaking the fuse link when it is desirable to interrupt the circuit under normal loads thus dispensing with the use of a circuit breaker in series with the fuse cutout and permitting the operation of the fuse cutout to open circuit position without producing injurious arcing between the fuse contacts together with a simplified latching mechanism which is easy to "set up" by a lineman wearing linemen's heavy gloves and the like.

A further object of this invention is to provide a new and improved re-cocking mechanism which is accessible from the exterior of the door of the cutout allowing a simplified re-cocking of the load break mechanism.

The novel features that are characteristic of the invention are set forth with particularity in the appended claims. The invention itself, however, both as to its organization and method of operation together with additional objects and advantages thereof will be understood by the following description of specific embodiments when read in connection with the accompanying drawings in which:

Fig. 1 is a side view, a portion of which is in section showing a housed fuse cutout embodying the inventive concepts;

Fig. 1-a is a perspective view showing the configuration of a link break member used in the embodiment shown in Figs. 1 through 5;

Figs. 2 through 5 are semidiagrammatic views showing the sequential actuation and relative position of the parts during operation of the link break means and opening of the entire door assembly to remove same from the cutout;

Fig. 6 is a side view, a portion of which is in section showing an alternative embodiment of closure assembly employing similar inventive concepts;

Figs. 7 through 10 inclusive are semidiagrammatic views similar to Figs. 2 through 5 showing the sequential operation of the alternative embodiment shown in Fig. 6; and

Fig. 11 is a fragmentary sectional view showing in enlarged detail the re-cocking mechanism of the alternative embodiment shown in Fig. 6.

Returning to Fig. 1 of the drawings, it is to be understood that a more complete description of the operating features of the cutout may be found in my Patent No.

2,820,868 aforementioned. For purposes of this case suffice it to say that the embodiment of the invention herein disclosed includes an insulating housing H having an open front and bottom with a lever comprising a door D of insulating material for closing the open front. The housing H is formed with a top portion 15, back portion 16, and side walls 17 and 18 (only one side wall being shown). Some designs may prefer to leave the top open (not shown) for double venting purposes.

5 Hanger means 19 is disposed centrally of and spaced from the top and bottom of the housing extending outwardly from the rear wall 16 to conveniently mount the cutout to a cross-arm or the like.

10 Mounted on the interior of the housing and on back walls 16 are spaced upper and lower terminals means 22 and 23 respectively. The upper terminal means 22 include contact means 24 here shown comprising U-shaped contacts 25. An electrical conductor 20 is shown semidiagrammatically attached to the upper terminal means 22. The lower terminal means 23 has contact means 27 here shown in the form of a U-shaped contact blade 28 which engages a contact sleeve 32 which will be more fully described hereinafter. The lower terminal means 23 is adapted to fixedly and electrically engage an electrical conductor 21 here shown semidiagrammatically.

15 A closure or door assembly 30 comprises the link break mechanism 41, the latching mechanism 50, the door D, contact sleeve 32, and the fuse tube 34. All of these portions of the closure assembly 30 are removable 20 as a unit from the cutout by virtue of pivotal mounting of the entire closure assembly 30 about pins (not shown) formed in the side walls of the housing which engage conventional trunnions 31 which are formed at the bottom of contact sleeve 32 in accordance with standard 25 procedure.

30 As shown the fuse tube 34 is adapted to electrically bridge the upper and lower terminals 22 and 23 by means of a fuse link 37 which is disposed interiorly of the fuse tube and having a metallic head thereon which 35 engages cap 35 at its upper end and is fixedly and firmly mounted to the outside of the contact sleeve 32 by means of a thumb screw 38. The electrical connection for the cutout being through the terminal means 22 to upper contact 25, fuse tube head and cap 35 through the fuse link 37 to thumb screw 38, through the contact sleeve 32 to lower contacts 28 and ending with lower terminal 23.

35 Means 41 for breaking the link 37 is provided by an assembly comprising a link break member 42 which is 40 rectangular in shape and mounted in suitable slots 49 formed in the side walls of the contact sleeve 32. As shown in perspective view 1-a link break member 42 is formed with transverse extending pins 44 and extending shoulders 42-a, the latter being adapted to engage 45 and slide in the side walls of slots 49. It will be further noted that the slot 49 is parallel with the axis of fuse tube 34 and serves to guide link break member up and down in a vertical plane as shall become apparent hereinafter.

50 Means for moving link break member 42 downwardly to impinge upon the tail 37 of the rupturable link is provided by a lever member 45 which is rotatably mounted on a pivot pin 47 which is mounted on the contact sleeve 32. As shown in Fig. 1 of the drawings, the lever member 45 is formed with an elongated slot 48 which is 55 adapted to fit over and engage one of the extending pins or ears 44 of the link break member. Lever member 45 is further formed with a square aperture at the marginal lower surface which engages a cocking mechanism as shall be later described.

60 It will be seen that movement of lever arm 45 in a counter-clockwise direction will cause slot 48 which is

curvilinear in shape to move link break member 42 downwardly in the guide slots 49 so that the end surface 43 of the link break member will engage the fuse link causing the weakest portion thereof to rupture.

The cocking and load imparting mechanism for moving link break member 45 in a counter-clockwise direction is denominated by the reference numeral 50. As shown, the cocking mechanism comprises an elongated member 51 which is pivotally mounted at 52 and the lower end of which is formed with a projecting portion 53 which extends through a suitable aperture formed in the lower end of offset back wall tab 32a of the contact sleeve 32 for coaction with lever member 45. Extending portion 53 is preferably square in cross-section so as to operatively fit within aperture 46 in lever member 45.

The upper end of member 51 is formed with an offset end portion 54 which is adapted to engage a pivotal latch member 55 which pivots about point 56 and has a hook-like face 58 which engages the side walls defining aperture 59 formed in the upper portion of the offset back wall tab 32a of the contact sleeve 32. It will be noted that the lever 51 is biased in a clockwise direction by virtue of a leaf spring 36 which is disposed in the lower half of member 51 as viewed in Fig. 1 of the drawings.

The door D is formed with a pull ring 39 at its upper outer extremity and at its lower extremity is formed with a U-shaped metallic portion 30b having inwardly directed metallic projections 30a which are pivotally mounted relative to the contact sleeve about pivot pin 47. Thus, it is seen that the contact sleeve 32 and the door D are relatively movable one to the other, as best illustrated in Fig. 3 of the drawings.

In operation, assume the parts are in the position shown in Figs. 1 and 2 of the drawings, i.e., the fuse link is held tightly in circuit completing position by thumb screw 38. Latch member 55 is disengaged from latching aperture walls 59 allowing free opening movement of the door D relative to the contact sleeve 32. Thus, a downward pull on pull ring 39 causes rotation of the outer door D around pivot 47 so as to cause movement to the position shown in Fig. 3 of the drawing whereby lever 51 and dog projection 53 moves to the left and the latter engages aperture 46 of lever member 45, under the influence of spring 36 while the contact sleeve 32 and tube 34 remain in the vertical position shown. This is the setting up or cocking of the mechanism for the link break operation which follows on the upward movement of the door as shown in Fig. 4 of the drawings.

As the door D is moved upwardly, lever member 45 pivots about pivot point 47 causing cam surface of slot 48 to force link break member 42 downwardly in slots 49 so that bottom edge surface 43 impinges upon the link 37 causing the latter to rupture at the fusible section. Leaf spring 36 retains the dog projection 53 in engagement with aperture 46 of lever member 45 during this operation. The aforementioned movement of member 51 about pivot 52 causes the upper end 54 to engage latching hook 55 to move face 58 so as to be set up to engage surface 59 when the door D reaches the top of its stroke.

The closure assembly 30 is now in position to be removed from the cutout about the trunnions 31 as shown schematically in Fig. 5 of the drawings. After the door assembly 30 has been removed from the housing, the lineman normally inserts a new fuse link within the fuse tube 34 in preparation of replacing the door assembly 30 back within the cutout. Heretofore, it has been exceedingly difficult to get the parts of the closure assembly back into the relationship shown in Figs. 1 and 2 of the drawings.

In the instant device this is accomplished relatively simply by having a lineman engage insulated push button 60 which extends through the exterior wall of the door D. By pushing the button 60 inwardly, lever member 51 is rotated in a clockwise direction causing dog 53 to

release from engagement with aperture 46 in lever member 45 and simultaneously causes upper end of the latching member 54 to engage the inboard tooth 57 of latching member 55 to set up the parts back to their original

position as shown in Figs. 1 and 2 of the drawings. The cutout is now ready, after insertion of the closure assembly back within the housing, for normal operation and when desired the link 37 may again be broken to interrupt the circuit without the use of a circuit breaker or the like.

A second embodiment shown in Figs. 6 to 11 inclusive has a different link break load imparting assembly and a slightly different arrangement of parts for the recocking lever and latching means 50'. Substantially similar

parts have retained identical reference numerals to the embodiment shown in Figs. 1 through 5. More particularly, the link break means 41' shown in Fig. 6 comprises a generally cylindrical member 42' having a vertical rack portion 64 in vertical alignment with the axis 20 of the fuse tube 34. A pinion 63 is rotatable about pivot pin 47' so as to cause the rack link break member 42' to move downwardly such that the lower portion 43' engages the link 37 causing the latter to rupture. A square aperture 46' in member 42' is engageable with dog 53' on lever 51' as shown in Fig. 8 of the drawings.

Rather than the apertures in the back wall of the contact sleeve 32, the present embodiment has a transverse cross pin 67 formed in the side walls of the contact sleeve which is engageable by hook portion 58' of latching member 55' for latching the door D to the contact sleeve and fuse tube 34, for removal of the closure assembly 30 from the cutout. A torsion spring 65 biases the lever member 51' in a clockwise direction thereby dispensing with a spring for the push button 60'. It is thus seen that the spring 65 serves the dual function of biasing the lever member 51 and push button 60 rather than relying on the two springs 36 and 62 shown in Fig. 1. This is shown in enlarged fragmentary sectional view, Fig. 11.

The operation of the second embodiment is substantially identical to that of the first embodiment, the recocking operation by pushing button 60' inwardly is identical to that of the first embodiment.

It is thus seen that in both embodiments an exceedingly simple method of accomplishing re-cocking is provided for setting up the link break mechanism. A lineman, wearing heavy lineman's gloves may easily re-cock the device when inserting a new fuse link and the device may be easily and quickly returned to operative position in the cutout.

Although specific embodiments in the invention have been shown and described, it is with full awareness that many modifications thereof are possible. The invention, therefore, is not to be restricted except as insofar as is necessitated by the prior art and by the spirit of the appended claims.

What is claimed as the invention is:

1. In a fuse cutout, in combination, a fuse tube including a pair of relatively spaced terminal contacts exteriorly thereof, a fuse link in said tube interconnecting said contacts and link break mechanism carried by said tube, said mechanism comprising a rack slidable in parallelism with the axis of said tube, a rotatable segmental pinion engaging said rack and having an arcuate portion terminating in a slot, a lever movable about the axis of said pinion in a plane substantially paralleling the axis of said tube, a pinion latch carried by said lever and normally engaging said arcuate portion of said pinion when said lever is in one position in said plane and engageable in said slot when said lever is in a second position in said plane, a second latch carried by said lever and engageable with said tube, and normally disengaged therefrom when said lever is in said one position, a biasing control lever carried by the first mentioned lever and interconnecting said pinion latch and second latch, a biasing spring

engaging said control lever for actuation of said pinion latch and second latch to latching position simultaneously, and a manually engageable re-cocking button engageable with said lever and operative, when engaged, to overcome the biasing spring to return the parts to normal position.

2. In a fuse cutout having a fuse tube including a pair of relatively spaced terminal contacts and a fuse link in said tube electrically connecting said contacts, the combination of link break means including a first member engaging a portion of said fuse link and movable generally parallel to the axis of said tube to rupture said fuse link and a rotatable member engaging said first member and including latch receiving means, an operating lever movable about the axis of said rotatable member, a control lever carried by said operating lever and including latch means, a spring engaging said control lever and biasing said latch means toward engagement with said latch receiving means, whereby when said latch means engages said latch receiving means said first member is mechanically coupled to and moves in response to move-

ment of said operating lever, and a manually operable re-cocking button engageable with said control lever and operative to overcome said biasing spring and disengage said latch from said latch receiving means.

5. In a fuse cutout having a fuse tube including a pair of relatively spaced contacts and a fuse link within said tube electrically connecting said contacts, the combination of link break means engaging a portion of said fuse link for rupturing said fuse link, actuating means for said link break means including a pivotally mounted lever and connecting means for mechanically coupling said actuating lever and said link break means, and manually operable re-cocking means engageable with said connecting means and operative to uncouple said link break means and said lever.
